UNITED STATES PATENT OFFICE.

EDWARD FRIES, OF MOORES, PENNSYLVANIA.

PIT-FLASK FOR CASTINGS.

1,345,161.

Specification of Letters Patent. Patented June 29, 1920.

Application filed October 11, 1919. Serial No. 330,076.

To all whom it may concern:

Be it known that I, EDWARD FRIES, a citizen of the United States, and a resident of Moores, county of Delaware, State of Pennsylvania, have invented certain Improvements in Pit-Flasks for Castings, of which the following is a specification.

My invention relates to certain improvements in flasks used in the production of 10 large castings.

One object of my invention is to provide a flask which can be permanently located in a pit and in which the mold can be built up prior to casting.

15 A further object of the invention is to make the walls of the flask movable and adjustable to accommodate molds of different sizes and to make the bottom supports of the flask adjustable for the same purpose.

20 A still further object of the invention is to construct a flask which can be permanently located in a pit in the molding floor so as to avoid the necessity of having a number of duplicate flasks and to economize in floor space heretofore used in storing unused flasks.

25 Another object of the invention is to prevent accidents due to the breaking of a flask, or the parts of a flask, by allowing the 30 molten metal to flow into a pit rather than over the molding floor.

Still another object of the invention is to provide a flask in which a bottom plate having a mold thereon can be inserted in the 35 flask and can be withdrawn therefrom with the casting.

In the accompanying drawings:

Figure 1 is a perspective view of my improved flask located within the pit and showing 40 the cope located on the flask and the parts ready for pouring;

Fig. 2 is a plan view of the flask;

Fig. 3 is an end view;

Fig. 4 is a side view;

45 Fig. 5 is a perspective view of the mold mounted on the bottom plate;

Fig. 6 is a perspective view showing the arrangement of the sections of the mold in the flask; and

50 Fig. 7 is a sectional view showing the flask within the pit and the cope located above the flask ready for pouring.

1 is a pit, of any depth desired, and located in this pit is the flask 2 consisting of 55 end members 3 and side members 4 and 4^a. The side member 4^a is fixed and the side

member 4 is adjustable toward and from the member 4^a. In the present instance, the side member 4 has extensions 5 which overlap the recessed portions 6 of the end members 3. 60 In order to hold the side member 4 in the position to which it is adjusted a series of holes 7 are made in each end member and pins 8 are driven in these holes. When the mold is in position, wedges 9 are driven in 65 the space between the pins and the side members so as to lock the mold firmly in position. The lower end of the side member may be held in any manner desirable and, in some instances, duplicate sets of holes for the pins 70 may be formed in the end members, as shown by dotted lines in Fig. 2.

Located in the flask is a bottom board 10 supported on bars 11, which extend through openings 12 in the end members of the flask. 75 These openings 12 are located so that the bottom board can be elevated to the height desired, according to the size of the mold, the parting being at the upper edge of the flask.

80 13 are a series of openings in the upper portion of the flask, in the present instance cruciform in shape, to allow for the escape of gas from the mold during the pouring operation. In the present instance, the flask 85 is of such a size as to accommodate the mold of a locomotive cylinder saddle, in which is contained the cylinder, the cylindrical valve and the passages leading to and from the cylinder and the valve.

90 In Fig. 6, I have illustrated the flask with the sectional mold located therein showing the detachable walls *a* of the mold, the section *b* forming the cylindrical valve chamber and the ports, the end members being 95 recessed to form one-half of the cylinder, the other half being formed in the mold carried by the cope, as illustrated in Fig. 7.

100 The flask is adjusted according to the mold and when once adjusted a mold can be assembled within the flask and sand rammed between the walls of the flask and the mold, then the cope is placed in position and the pouring head is also located in position, as in Fig. 1, then the metal is poured into the 105 flask and in time the casting can be removed with the bottom plate by first removing the cope and withdrawing the mold and casting on the bottom plate, leaving the flask within the pit. The pit is then cleaned out to receive another bottom plate with another 110 mold assembled thereon.

It will be understood that the slings which are attached to the bottom plate and the mold are carried from one place to another and remain on the bottom plate when the 5 plate is inserted in the flask. Loose sand is packed around these slings, which project to a point near the upper end of the flask so that they are entirely embedded in the mold while the mold is being poured, and when 10 the cope is removed, after pouring, the sand is removed sufficiently to allow the hooks of a crane to engage the slings and withdraw the bottom plate with the casting after the wedges retaining the side members have been 15 removed.

By this arrangement, a single flask can be used for any number of molds without removing the flask from the pit. This prevents the accumulation of a large number of 20 flasks heretofore used in foundries where large castings are made as, in the ordinary method, the flask was removed each time a casting was made, and another flask placed in position. The flasks, after the castings 25 were removed, were piled either on the inside or on the outside of the building, occupying valuable space which is now used more advantageously.

Heretofore, particularly in casting cylinders of locomotives, each special size of cylinder had to have a flask of a corresponding size. This necessitated carrying a large 30 number of flasks in storage, or providing special flasks when cylinders of a special 35 size were to be made.

By my improvement, I am enabled to make a single fixed flask, which can be adjusted to fit molds of different dimensions. Furthermore, where intricate molds are 40 used, the several cores can be assembled on the base mold, being supported only by the bottom plates, thus insuring more accurate castings than where the mold and the cores are assembled within a drag section of a 45 flask.

While I have shown one side member arranged to be adjusted, it will be understood that the other side member may be adjusted if found necessary, and while I have shown 50 pins and wedges for holding the adjustable side members in position, other means may be used, if desirable.

I claim:

1. The combination in a flask adapted to 55 be located in a pit, of fixed end walls and side walls located between the end walls, one

of said side walls being adjustable; and an adjustable bottom located within the flask and supporting the mold.

2. The combination of a flask adapted to 60 be permanently located within the pit and having end walls and side walls, one wall being adjustable toward and from the other wall; a bottom plate carrying the bottom section of the mold, the parting being at the 65 upper edge of said mold; a cope having the upper section of the mold formed therein and placed on the lower section; and a pouring section located on the cope.

3. The combination in a flask adapted to 70 be permanently located in a pit, of a fixed side wall and end walls recessed at the upper end; a movable side wall having extensions adapted to the recessed portions of the end walls; a series of holes in each end of each 75 end wall; pins adapted to the holes; and wedges between the pins and the movable side wall so as to hold the said side wall in the position to which it is adjusted.

4. The combination of a flask having end 80 and side walls, said flask being permanently located in a pit, the upper portion of the flask extending above the pit, said flask having a movable side wall; means for holding the said side wall during the casting operation; a bottom plate adapted to the flask; means for supporting the bottom plate in the flask, the bottom mold being carried by the bottom plate and extending to a point below the parting line of the flask; detachable mold sections mounted on the bottom mold so as to bring the mold up to the parting line; and a cope mounted on the flask and carrying the balance of the mold.

5. The combination of a flask; a pit in 95 the molding floor in which the flask is located, the flask extending above the floor; a series of holes in the lower portion of each end wall of the flask; bars located in the holes; and a bottom plate located within the 100 flask and supported by the bars.

6. The combination of a fixed flask having end and side members; a removable bottom plate located within the flask; means for supporting said plate; and slings attached to 105 the bottom plate at each side of the mold, said slings, before the metal is cast, being embedded in sand forming part of the mold, so that, after the casting is made, the bottom plate, with the casting, can be removed 110 by a crane engaging the slings.

EDWARD FRIES.
